CLAIM

The ornamental design for a multipurpose tool as shown and described.

DESCRIPTION

FIG. 1 is a front, right and top perspective view of a multipurpose tool, showing my design.

FIG. 2 is a rear, left and bottom perspective view thereof.

FIG. 3 is another front, right and top perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 2; and, FIG. 11 is another front, right and top perspective view of the multipurpose tool in another state.

The broken lines depict portions of the multipurpose tool that form no part of the claimed design. The dot-dash broken lines in FIGS. 2 and 10 depict the boundaries of the enlargements that form no part of the claimed design.

1 Claim, 11 Drawing Sheets(56)
